DESCRIPTION

FIG. 1 is a front perspective view of an ignition switch insulating heat shield showing our new design;

FIG. 2 is a rear perspective view thereof;

FIG. 3 is a left side elevational view thereof, the right side being a mirror image;

FIG. 4 is an elevational view of one end thereof, the other end being a mirror image;

FIG. 5 is a front elevational view thereof; and

FIG. 6 is a rear elevational view thereof.
